IGNITION COMPOSITION COMPRISING
PYRO-LEAD SALT-CHLORATE

Lawton A. Burrows, Woodbury, and George A. Noddin, Wenonah, N. J., assignors to E. I. du Pont de Nemours & Company, Wilmington, Del., a corporation of Delaware

No Drawing. Application September 30, 1939,
Serial No. 297,272

8 Claims. (Cl. 52—4)

This invention relates to new and improved ignition compositions, and more particularly to compositions adapted to serve as top charges in blasting caps.

Ignition compositions of the type contemplated by this invention have numerous applications, for example, in various forms of squibs and blasting caps used in the initiation of explosive charges, particularly in electric blasting caps, as well as in other devices where a small charge of a deflagrating explosive is ignited by means of an electric current.

A particular field for such composition is as a loose ignition top charge in an electric blasting cap. It is essential here that the composition be capable of ready ignition on application of the heat from the passage of an electric current through a fine, highly-resistant wire in contact with the loose material. Ignition must not only be certain but it must take place with the use of a low firing current. The composition must also be sufficiently stable so that its ability to ignite will be uniform and unaffected by storage, even under unfavorable conditions. On the other hand, such a composition must not be unduly sensitive, such, for example, that it will be fired by small electrostatic discharges or be sensitive to slight jars and shocks. It must likewise give off sufficient flame and heat on ignition to bring about the firing of an adjacent explosive charge.

No one chemical compound has been found which possesses all the properties desirable for such use, and none of the mixtures of ingredients heretofore proposed has been entirely satisfactory.

The object of the present invention is an improved ignition composition. A further object is an ignition composition possessing favorable firing characteristics and having the ability to ignite an adjacent explosive charge from its combustion flame. A still further object is an ignition composition which is satisfactory as a loose top charge in an electric blasting cap. Additional objects will be disclosed as the invention is described more fully hereinafter.

We have found that the foregoing objects are accomplished by employing as an ignition composition smokeless powder in finely divided condition, together with a lead salt of a nitrophenol. The lead salts of various nitrophenols are adapted for use in the above manner, for example, the salts of dinitrophenol, trinitrophenol, dinitrocresol, and the like. A lead salt of dinitro-ortho-cresol is our preferred salt for use. More specifically, we find it desirable to employ a com-

plex or double salt of lead nitrate with a lead salt of a nitrophenol, particularly the double salt of lead nitrate with 4,6-dinitro-ortho-cresol, which may be designated more exactly as 3,5-dinitro-2-hydroxy-1-methyl benzene, as is discussed more at length in the Burrows and Filbert application, Serial No. 171,512, filed October 28, 1937.

We find it desirable, furthermore, to include an oxidizing agent in the ignition composition, in addition to the comminuted smokeless powder and the above complex lead salt of a nitrophenol. As the preferred oxidizing agent we employ potassium chloride.

As examples of specific embodiments of our invention, we may cite the following:

Example 1

20 A 65-25-10 blend of ground pyro smokeless powder, a double salt of lead nitrate and a bis basic lead salt of 4,6-dinitro-ortho-cresol, and potassium chloride, respectively, was grained with a suitable solution, dried, and screened. The firing current required for ignition of the 25 above loose charge was 0.299 ampere. The charge consistently failed to give detonations when a $\frac{1}{2}$ " steel ball was dropped upon a layer of it from a height of 10". The composition had satisfactory ignition ability when fired in the 30 presence of other explosive charges.

Example 2

An intimate mixture was prepared and grained, comprising 50 parts pyro powder, 25 parts of the 35 complex lead salt used in Example 1, and 25 parts of potassium chloride. After drying and screening, the loose charge was found to have a firing current requirement of 0.318 ampere. The 40 composition gave a drop test of 6" with the steel ball described in Example 1, and under the same conditions. The composition was satisfactory in its lack of sensitiveness to the effect of small static charges.

Example 3

45 A blend was prepared comprising a grained mixture of 75 parts of comminuted pyro smokeless powder and 25 parts of a double salt of lead nitrate with a bis basic lead salt of 4,6-dinitro-ortho-cresol. After drying and screening, the 50 composition possessed a minimum firing current requirement of 0.309 ampere. The composition failed consistently to fire when the steel ball of Example 1 was dropped on a layer thereof from a height of 40". The composition was like-

wise satisfactory in the absence of susceptibility to electrostatic charges.

The compositions of the type illustrated in the foregoing examples are particularly adapted for use as loose ignition charges in electric blasting caps. Preferably, we use compositions within the range of 50-75% of pyro smokeless powder, 1-25% potassium chlorate, and 15-25% of the complex salt of lead nitrate with dinitro-ortho-cresol. If no inorganic oxidizing agent is included, a desirable range of compositions will be 75-85% pyro powder and 25-15% of the lead double salt. We find such compositions of particular importance as top charges in electric blasting caps containing lead azide as the primary detonating explosive, the azide being superposed on a base charge of tetryl or other suitable material. The composition will be particularly useful in electric blasting caps of the bridge plug type, where a loose ignition charge surrounds the bridge wire connecting the two leg wire terminals below the plug. The preferred compositions are uniform in rate of burning, but sufficiently slow to be satisfactory in series firing.

It has been stated that one of the principal ingredients of the composition is ground smokeless powder. The grade known as pyro powder will be the one preferably used, which signifies the grade made from nitrocellulose substantially soluble in a mixture of 2 parts by volume of ether to 1 part of ethyl alcohol, and having a nitrogen content of about 12.6%.

The lead salt used may be such a salt of any of the nitrophenols, but preferably will be a complex salt of lead nitrate with the lead salt of 4,6-dinitro-ortho-cresol. Our preferred salt may be designated as lead nitrato-bis basic lead-4,6-dinitro-ortho-cresylate monohydrate, and has the following formula:

As stated, we find it desirable, though not essential, to include an inorganic oxidizing agent as an ingredient of our ignition composition. Potassium chlorate is the preferred salt for such use because of its uniform performance. Other

inorganic oxidizing salts may be used in its place, however, such as various nitrates, chlorates, perchlorates, and the like.

Our ignition composition has been designed particularly for use as a top charge in electric blasting caps. It will be capable of application in other fields, however, where similar properties are advantageous; for example, it may be used in ordinary blasting caps, delay caps, electric squibs, 10 flashlight compositions, electric fuses employing an ignitable composition, and elsewhere.

We have described our invention at length in the foregoing, but it will be understood that many variations may be made in exact compositions without departure from the spirit of the invention. We wish to be limited therefore by the following patent claims:

1. In a blasting initiator, an ignition composition consisting essentially of a loose charge of comminuted colloided smokeless powder and a lead salt of a nitrophenol.
2. In a blasting initiator, the composition of claim 1, in which the nitrophenol is dinitrophenol.
3. In a blasting initiator, the composition of claim 1, in which the nitrophenol is a dinitro-cresol.
4. In a blasting initiator, an ignition composition consisting essentially of comminuted colloided smokeless powder and a complex salt of lead nitrate with a bis basic lead salt of 4,6-dinitro-ortho-cresol.
5. In a blasting initiator, an ignition composition consisting essentially of 75-85% of comminuted colloided smokeless powder and 25-15% of a complex salt of lead nitrate with a bis basic lead salt of 4,6-dinitro-ortho-cresol.
6. In a blasting initiator, an ignition composition consisting essentially of comminuted colloided smokeless powder, an inorganic oxidizing agent, and a lead salt of a nitrophenol.
7. In a blasting initiator, an ignition composition consisting essentially of comminuted colloided pyro nitrocellulose, potassium chlorate, and a complex salt of lead nitrate with a bis basic lead salt of 4,6-dinitro-ortho-cresol.
8. In a blasting initiator, an ignition composition as the top charge in an electric blasting cap, said composition consisting essentially of 50-75% of colloided pyro nitrocellulose, 1-25% of potassium chlorate, and 15-25% of a bis basic lead salt of 4,6-dinitro-ortho-cresol.
